UNITED STATES PATENT OFFICE.

HARRISON H. ROUNTREE, OF CHICAGO, ILLINOIS.

DESIGN FOR A SPROCKET-WHEEL AND CHAIN GUARD.

SPECIFICATION forming part of Design No. 26,985, dated April 27, 1897.

Application filed March 27, 1897. Serial No. 629,621. Term of patent 3½ years.

To all whom it may concern:

Be it known that I, HARRISON H. ROUNTREE, a citizen of the United States, and a resident of Chicago, in the county of Cook and State of Illinois, have invented and produced a new and original Design for Sprocket-Wheel and Driving-Chain Guards for Bicycles, of which the following is a specification.

In the accompanying drawings, Figure 1 is a perspective view of a guard embodying my design. Fig. 2 is a transverse section on line 2 2 of Fig. 1.

A guard or shield of my design consists of a marginal frame A the edges of which are continuous and unbroken and provided with a flange A', which projects laterally therefrom, so that it will cover the driving-chain when the guard or shield is applied to a bicycle.

At its front end a guard or shield of my design embodies a circular web A² the rear

side of which is connected with the practically parallel longitudinal members of the marginal frame A by webs or braces a. In the rear of the circular web A² the opposite sides or longitudinal members of the marginal frame are connected by a web of open-work so arranged as to form the word "America," combined with an ornamental scroll, as shown.

I claim.—

The design for a sprocket-wheel and driving-chain guard for bicycles, substantially as herein shown and described.

In testimony that I claim the foregoing as my invention I hereunto set my hand, this 20th day of March, 1897, in the presence of two witnesses.

HARRISON H. ROUNTREE.
